Walter S. Loring
by Chas. T. Perkins Attorney

UNITED STATES PATENT OFFICE.

WALTER S. LORING, OF PLYMOUTH, MASSACHUSETTS.

DESIGN FOR A GAME-BOARD.

57,982.

Specification for Design.

Patented May 24, 1921.

Application filed October 19, 1920. Serial No. 418,099. Term of patent 14 years.

To all whom it may concern:

Be it known that I, WALTER S. LORING, a citizen of the United States, residing at Plymouth, in the county of Plymouth and State of Massachusetts, have invented a new, original, and ornamental Design for a Game-Board, of which the following is a specification, reference being had to the accompanying drawing, forming part thereof.

The figure is a plan view of a game board showing my new design.

A rectangular game board upon which is pictured Plymouth Rock in a central dial and one house of pilgrim historic interest in each of the four corners of the board. The main surface of the board, exclusive of the above designated picture portions, is laid

out in rectangular areas presenting a checkered effect so connected as to describe a pathway over which the men used in the game traverse in the course of their progress.

I claim:

The ornamental design for a game board as shown.

In testimony whereof I have hereunto set my hand in presence of two subscribing witnesses, this twentieth day of September, 1920.

WALTER S. LORING.

Witnesses:

ALICE G. SULLIVAN,
CHAS. F. PERKINS.
